(57) **CLAIM**

We claim, the ornamental design for a confectionary, as shown and described.

DESCRIPTION

FIG. 1 is a perspective view of a confectionary, showing our new design in an exemplary embodiment;

FIG. 2 is a side elevation view of the embodiment shown in FIG. 1, the opposite side view being a mirror image thereof;
FIG. 3 is a top plan view of the embodiment shown in FIG. 1;
FIG. 4 is a bottom plan view of the embodiment shown in FIG. 1;

FIG. 5 is a front elevation view of the embodiment shown in FIG. 1 the back view being a mirror image thereof;

FIG. 6 is a perspective view of a confectionary, showing our new design in an exemplary embodiment;

FIG. 7 is a side elevation view of the embodiment shown in FIG. 6, the opposite side view being a mirror image thereof;
FIG. 8 is a top plan view of the embodiment shown in FIG. 6;
FIG. 9 is a bottom plan view of the embodiment shown in FIG. 6; and,

FIG. 10 is a front elevation view of the embodiment shown in FIG. 6 the back view being a mirror image thereof.

The stippling shown in FIGS. 6-10 represents a contrast in appearance.

Also, references to “side,” “top,” “bottom,” “front,” and “back” in the Figure Descriptions are not necessarily meant to require any specific orientation of the article as viewed. A confectionary according to the claimed design may be used in any orientation.
